COMBINED GAME AND AMUSEMENT APPARATUS

Peter Kyska, Chicago, Ill.

Application December 1, 1941, Serial No. 421,116

7 Claims. (Cl. 273—120)

My invention is directed to a novel game and game apparatus for amusement. More specifically it is directed to an improved apparatus capable of being used by adults as well as a toy, and which includes a plurality of inclined tracks from which a series of balls are adapted to roll to be selectively delivered and deposited upon either one tiltably mounted play table or bed, or successively and alternately upon two such playing tables or beds, upon which the balls roll to be deposited upon a plurality of fulcrumed levers having indicia designations and certain of which levers are adapted to be optionally held against pivoting ball-discharging movement by staggered pegs or pins of a rotatable shaft element.

It is an important object of my invention to provide a novel game apparatus, having either one or a pair of tiltably or rockably mounted beds; a plurality of chutes disposed substantially about the beds; a rockable pivotally mounted foot adapted to be operated by either one or both players whereby either player may cause the balls to be successively released by suitable mechanism to be conveyed to either of the tilttable beds.

A further object of my invention is the provision of a novel game apparatus of the general type indicated in the preceding paragraphs and having a plurality of adjacent pivoted and fulcrumed indicia-bearing lever members, each of which normally rock with the weight of a ball thereon, and which game has means and mechanism including a shaft bearing rows of spaced apart staggered pins so that said shaft may be placed in one of a number of positions to non-uniformly cause the pins of one row to hold the rocker levers against pivoting and ball-releasing movement.

A further object is the provision of a game having one or more rocker beds upon which the balls are adapted to be successively delivered according to the desire of either a single player or of one of a plurality of players, and which have a plurality of rocker levers fulcrumed so that portions of said levers are disposed in exit holes in the lower end of the bed, in combination with indicia bearing player operated rotatable obstructing member, which member is adapted to obstruct a part of said levers against ball releasing movement and an indicia bearing rotatable shaft drivingly connected to said rotatable obstructing member, thereby providing solely a "chance" resulting score impossible of predetermination of the player.

Other and further important objects of my

invention will be apparent from the following description and claims.

This invention (in a preferred form) is illustrated and such illustration described in the following:

On the drawings:

Fig. 1 is a top plan view of one form of my invention showing portions broken away at the left thereof, particularly of the left playing table and other parts.

Fig. 2 is an enlarged elevation of a fragment showing a portion of the indicia bearing roller and portions of the pin-carrying shaft and showing the central pivoted and depending portions of some of the levers.

Fig. 3 is an enlarged cross sectional view taken on line 3—3 of Fig. 2 illustrating one of the pivoted lever elements.

Fig. 4 is a cross sectional view taken on line 4—4 of Fig. 2.

Fig. 5 is an enlarged side elevational view of a fragment of my invention taken on line 5—5 of Fig. 2.

Fig. 6 is a rear elevational view looking at the top of Fig. 1 and showing the rear frame support and rockable train or track and other parts.

Fig. 7 is an enlarged elevational view taken on line 7—7 of Fig. 1 and looking toward the upper portion of Fig. 1.

Fig. 8 is an enlarged top plan view of a fragment of the delivery and lower end portion of the right hand ball chute, and taken substantially on line 8—8 of Fig. 6.

Referring to the drawings, reference numeral 10 designates a suitable frame of metal, wood or other suitable material. Numerals 10a and 10b designate the opposite side members which compose the frame side portions. The forward ends of each of the side bars or members 10a and 10b are secured by screws or equivalent means to the inner edge surfaces of the vertically extending legs or posts 16 and 17 respectively. Numeral 11 designates the back or rear bar or truss of the frame which is connected at its opposite ends to the side bars 10a and 10b respectively at the points of juncture therein. A forward strap or bar 12 is secured at its opposite ends to the lower ends of corner legs or supports 16 and 17. The intermediate leg or support 15 (Fig. 2) is connected at one of its ends by screws, nails or the like to the intermediate portion of transverse forward connecting bar 12, said connecting bar 12 being preferably so positioned that it will lay flat upon a table or supporting surface. The upper rear connecting bar 11 is shown in elevation in

Fig. 7, which is a cross sectional view taken on lines 7—7 of Fig. 1. A plurality of triangular corner segments 13 form corner braces. In the particular form of my invention illustrated in Fig. 1, wherein two playing tables are provided, I provide a vertical intermediate division panel 14 midway between the outer side bars 10a and 10b, which likewise extends from bar 11 to a point beyond 12 and is connected thereto. The rearward end of intermediate panel 14 is connected to the longitudinal rear bar 11 by suitable screws, nails or the like, and the forward end of said division panel 14 is connected by screws, nails, glue or equivalent means to the forward intermediate post 15 as illustrated in top plan view 15 of Fig. 1.

Numerals 18 and 19, illustrated in Fig. 7, represent vertically extending legs or supports and numeral 29 designates an intermediate vertically extending supporting leg or support, all of which legs are secured intermediate their ends by suitable fastening elements to the horizontal rear cross bar 1. Referring to Fig. 7, numeral 21 designates a horizontal base strap or bar which is adapted to lie preferably upon the table or other supporting surface, and said base bar 21 is connected by screws or equivalent fastening elements to the lower ends of legs or supports 18, 19 and 20 respectively, as illustrated in said Fig. 7.

As shown in Figs. 1, 2 and 7, a panel 22 of substantially rectangular form, though preferably having an inclined non-straight edge, the upper edge terminating in a central apex is mounted in a vertical plane with its lower edge coinciding with the upper edge surface of the rear horizontal frame cross bar 11. Said panel has an upper central opening 23 in which is mounted a ball delivery trough as hereinafter described, and has a pair of spaced apart openings 24 therein located at positions so that the balls may be delivered in the manner hereinafter described to the playing table from ball delivery means herein described. Said panel has a pair of spaced apart openings 25 and 26 substantially in the positions as illustrated in Fig. 7 and in which are mounted fulcrumed levers hereinafter described, and said panel also has a lower substantially central opening 27 therein through which suitably mounted hand levers extend for purposes hereinafter described. Said panel 22 is secured to the upwardly extending portions of rear legs 18, 19 and 20 by screws or equivalent fastening elements. The intermediate horizontal bar or strap 11 is preferably provided with a pair of downwardly opening recesses 28 and 30 as indicated in Fig. 7. The outer rearward ends of two ball-return troughs or chutes are supported under said troughs 31 and are secured to the lower edge of the rear cross bar 11 by screws or equivalent fastening elements (not shown) which pass through edge flanges of said troughs 31 and into said cross bar 11.

As shown in side elevation in Fig. 7 and in top plan view in Fig. 1, I provide a substantially rectangular panel 32 which is mounted with one flat surface directly against the rear surface of the panel 22, and which is above the upper end of the intermediate post 20 and upon the rear surface of said panel 22. This panel 32, made of metal or other suitable material, is provided with a pair of apertures or openings adjacent its side edges which register with the openings 25 and 26 of panel 22. These side openings in panel 32 are preferably formed by making a U-shaped cut in said panel 32 and bending the integral

tongues formed thereby perpendicularly with respect to said panel 32 and in a rearward direction to provide horizontally extending ears 33 which are formed with apertures through which pivot bolts 34 are inserted. Bolts 34 are shown as inserted through said ears 33 in a horizontal direction and said bolts pass through suitable apertures formed in the intermediate portions of lever 35 to thereby pivotally mount said levers 35 for pivoting movement in horizontal directions, one portion of said levers 35 projecting forwardly of panel 22 and the other portion thereof projecting rearwardly of panel 22 to points wherein said levers 35 will engage the under surface of the fulcrumed tiltable ball race hereinafter described. The rearward ends of said levers 35 are shown in dotted lines in Fig. 1 as beneath the said ball race. The two pivot bolts 34 have suitable nuts threaded on their outer ends to hold said levers 35 in position thereon.

The rectangular panel 32 also has a suitable aperture or opening registering with the opening 27 in panel 22, the edge of said opening being shown in Fig. 7.

A pair of levers 36 and 37 shown in top plan in Fig. 1 are pivoted by means of common pivot to the edge portion of panel 22 which edge portion is adjacent the opening 27, said common pivot, which may be a suitable screw or pin, passing through the intermediate crossed over portions of both of said levers 36 and 37 and into the edge portion of panel 22 to thereby mount said levers so that the opposite ends thereof extend on opposite sides of the panel 22 as indicated in Fig. 1. These levers are connected by suitable links hereinafter described to ball throw-out or ball discharge elements later herein described.

Description of ball delivery mechanisms and parts

As illustrated in Figs. 1 and 6, I provided a plurality of race-ways and a tiltable, rockable race whereby either one or more players may selectively and alternatively effect delivery of balls to either one or both of the playing tables hereinafter described. Referring to Figs. 1 and 6, numeral 41 designates a substantially rectangular base of wood, metal, or the like which has secured thereon two vertical ends posts 42 and 43 respectively at opposite ends of said base. Said posts or supports 42 and 43 may be formed of wood, metal or the like and extend in perpendicular direction as shown in Figs. 1 and 6.

Secured upon the intermediate portion and substantially midway between the ends of said base 41 are a pair of spaced-apart upwardly extending posts 44 and 45 respectively which are secured by screws or equivalent fastening means to the base 41. Numeral 46 designates a transverse normally horizontal pivot pin which is mounted in aligned apertures (not shown) formed in the upper ends of posts or supports 44 and 45. Said pin 46 provides a suitable fulcruming or pivot means for a tiltable, swingable and pivotable race hereinafter described.

Referring to Figs. 1 and 6, numeral 47 designates a channel-like trough or race of U-shape cross section which is preferably formed of metal and which has its outer end bent toward the playing table as designated and which has its opposite end bent and doubled back as indicated in Fig. 1, said doubled back end portion being designated by a numeral 48, and being thence bent to form a delivery spout por-

tion 49 which has its end mounted within the delivery opening of vertical panel 22.

Referring to the upper right end portion of Fig. 1, a second circuitous and curved ball-race 56 having bent receiving end 51 and a doubled back portion 52 and integral delivery spout 53 is mounted upon post or standard 43 so that said race is substantially inclined from its receiving end 51 to its delivery spout 53. The inclined ball race 47 is similarly secured by screws or equivalent means in similar inclined position upon the upper end of post or standard 42. The spout 53 of race 56 passes through and is mounted in the aperture 24 of vertical panel 22.

Referring to the doubled backed portions 48 and 52 of the curved inclined races 47 and 56, numerals 54 and 55 designate a pair of substantially triangular valves or gates which are pivoted on suitable vertically extending pivots as indicated, for movement in the horizontal plane. Each of said valves or gates 54 and 55 have an integral perpendicular extending flange along the inner edge hereof which acts as a stop or obstruction to the rolling ball when said valves are pivoted to obstruct the race in the manner illustrated at the upper right of Fig. 1. Each of said valves 54 and 55 have an integral horizontally extending aperture ear as indicated, and one end of the metal connecting links 56 and 57 are pivotally engaged in said ear respectively, the other end of said connecting links 56 and 57 being pivotally connected to the rear-most aperture ends of levers 36 and 37 as shown in Fig. 1.

As shown in the upper portion of Fig. 1, I provide an inclined channel-like ball race 59 which is substantially the shape of a common fish hook. The enlarged ball receiving end of said race shown at the center of Fig. 1 is designated by numeral 60, and an intermediate portion of said race is broken away to show other parts, and the lower or delivery end of said race is designated by numeral 59a, said delivery end terminating at a point immediately above the supporting post 44. A number of balls are adapted to be deposited by the operator in the uppermost receiving end 60 of race 59.

As shown in side elevation in reduced form in Fig. 6 and as shown in top plan view in Fig. 1, I provide a rockable, swingable and pivotal ball race 61, which is pivoted at its center on pivot pin 48, and which has its opposite ends bent at substantially obtuse angles as indicated in Fig. 6. The degree to which said ends are bent is that when said rockable ball race 61 is pivoted or rocked in either direction, the bent ends thereof will be substantially horizontal to provide for a ball rolling in either direction from the center of said rockable ball race to be deposited upon one or the other of the inlet ends of inclined ball races 47 and 56.

As shown in side elevation in Fig. 6, I rotatably mount a pulley 62 upon a suitable pin 63 which pin is mounted in horizontal position in suitable apertures (not shown) in the upper ends of posts 44 and 45, the upper end of post 45 being broken away in Fig. 6, said pulley 62 being of wood, metal or the like and preferably formed with edge annular grooves.

Numerals 64 and 65 designate a pair of levers, preferably made of metal, which have their lower ends pivotally connected to the rockable ball race 61 by suitable pivots 66 and 67, as shown in Fig. 6. These pivots 66 and 67 are equidistant from the central pivot of race 61. Secured upon

the upper portions of levers 64 and 65 respectively are two relatively short inclined channel-like troughs or chutes 68 and 69. These troughs or chutes 68 and 69 are secured in such positions that they are normally in a substantially inclined position as shown in Fig. 6, and these troughs or chutes 68 and 69 are in such position that their upper ends are directly below the delivery end 59a of the curved ball race 59. As shown in Fig. 6, the lower end inner surface of levers 64 and 65 ride on the annular surface of pulley or wheel 62.

As shown in Fig. 6, I provide a pair of deflecting shields or baffle elements 70 and 71 which are preferably of arcuate cross section and which have their lower ends bent angularly and secured by suitable pivots upon the intermediate portions of the rockable ball race 61.

Secured on the uppermost end of the inner post 45, and as shown in top plan in Fig. 1, is a substantially U-shaped bracket 72 which is in a position directly opposite and in alignment with the ball delivery opening of the end portion 59a of race 59. As the gravity impelled tendency of the balls in race 59 is to run to the lowest point, the foremost ball of the group of balls, or last ball, will roll to a position where it becomes impinged between the delivery end of race 59 and the U-shaped bracket 72. That is, a portion of the ball will be within the bracket 72 so that the ball is temporarily held in said impinged position directly above the upper ends of the troughs or chutes 68 and 69.

As the rockable ball race 61 is pivoted with its right hand end down and its left hand end uppermost, the lower surface of lever 64 rides along the annular surface of wheel or pulley 62 to raise the chute or trough 68 and cause the upper end of said chute 68 to slightly lift the foremost ball to disengage said ball from said impinged position to thereby cause the said ball to roll down the chute 68 and into and along the left hand end of rockable race 61. When said race is rocked into the opposite direction, namely so that its left hand end will be in lowermost position with the left hand bent end of ball race 61 resting upon the edge of the inclined race 47, thereupon the release ball rolling down said left hand end of race 61 will be rolled into the upper and delivery end of race 47 from where said ball continues to roll by gravity along and through race 47 to the delivery end thereof to be deposited upon the playing table.

When a ball is to be delivered through the opposite or right hand playing table shown in Fig. 1, the left hand end of the rockable ball race 61 is swung downwardly in the aforescribed manner, the foremost impinged ball is released and thereupon said ball rolls down and through chute 69 into the right hand portion of race 61, and upon the race 61 being rocked with the right hand end down, the ball is thereby delivered through race 60 to the right hand playing table.

Referring to Fig. 1, numerals 73 and 74 designate the two rockable playing panels forming the playing surfaces of playing tables which are formed of either wood, metal or the like, and each of which are of a size to loosely fit between the intermediate frame bar or panel 15 and the two side bars 10a and 10b respectively.

As shown in Fig. 1, at the right, the panels 73 and 74 are mounted similarly and in the following manner: The panel 74 is secured by screws or other equivalent method to the upper surface of a

bar or member 75 which has its opposite ends reduced, the rearward opposite reduced end thereof being journalled in a suitable aperture shown in dotted lines in Fig. 1 and formed in the rear frame bar 11. The forward end of said bar 75 is journalled in the aperture formed in the upwardly extending bent end of a metal bracket 76, which bracket 76 has its opposite end secured by screws or equivalent fastening elements (not shown) to the bottom cross bar 53 of the frame. The said mounted positions of each of said bars 75 is inclined downwardly toward the bracket 76 so that it will hold the playing panel 74 in correspondingly inclined positions so that balls will roll by gravity from points near the delivery spouts 49 toward the forward portion of the device.

Journalled adjacent the lower straight edge of the playing panel 74 are a pair of horizontal shafts 77. Each of the shafts 77 has its ends secured in a suitable aperture in the frame side bars 10b and 10a respectively and the other ends of each thereof secured in a suitable aperture in intermediate bar 14. Said shaft is shown in cross-section in Fig. 4 and a fragment thereof shown in side elevation in Fig. 2. Rotatably journalled on said shaft 77 in substantially adjacent positions are a plurality of rocker-like members 78 which have a normally downwardly depending counterweight portion 79 and each of which have a ball-receiving upper cup 80 as clearly shown in Figs. 2 and 4. Said rocker or lever members 78 are in alignment and in substantially adjacent positions on said shaft 77 as clearly shown at the left in Fig. 2.

Secured adjacent to and immediately above the intermediate journalled portions of the rocker members 78 is a horizontally extending strap 81 of metal, wood or other suitable material which is shown in cross section in Fig. 4. Said strap 81 acts as a stop element to stop the rolling balls to cause the balls to fall upon the cups 80 of the rockable members 78.

As shown in Figs. 1, 2 and 4, a rotatable indicia roller or shaft 82 is mounted in a horizontal position substantially adjacent the strap 81 and adjacent the central portions of the rockable members 78, and said indicia shaft 82 has its opposite reduced ends journalled in the intermediate bar 14 and frame side bar 10b. The end of said indicia shaft 82 which passes through the side bar 10b has secured thereon a suitable gear wheel or sprocket 84 and said end projects outwardly and horizontally to form a grippable handle 85 as shown at the right of Fig. 2.

The shaft 82 has affixed thereto a plurality of indicia 86, preferably numbers, in a substantially equidistant spacing or relationship as indicated in the right of Fig. 2. The said indicia, in my preferred form, is arranged so that four numbers are affixed in each row or sector circumferentially of the roller or shaft, in other words, said numbers being spaced with their centers substantially ninety degrees apart about each sector. In Fig. 2 I have illustrated circumferential lines 87 to illustrate the annular circumferential sectors of the surface of indicia roller or shaft 82.

Further, in the preferred form of my invention, all the respective sets of four or less numbers, each are so arranged that the respective numbers are in substantial alignment longitudinally of the roller or shaft of said numbers or in horizontal rows. Therefore, the shaft is adapted to be rotated into any one of a number of positions so that there is presented upwardly and to the play-

er's view, a selected horizontal row of indicia. Referring particularly to Figs. 1 and 2, numeral 88 designates peg carrying or pin carrying horizontal extending shaft which has one end reduced and journalled in the intermediate panel 14 and its other end reduced and journalled in side bar 10b, said latter end extending through and projecting outwardly from said side bar 10b as indicated at the right of Fig. 2. Said outwardly projecting end of pin shaft 88 has secured thereon a gear wheel or sprocket 89 whose teeth mesh with the teeth of sprocket 85. A plurality of pegs or pins 90 are secured in radially extending positions in suitable apertures of pin shaft 88 and in staggered relationship, though being preferably in substantially two perpendicular planes. Therefore, said pegs or pins 90 are preferably arranged so that the position of one horizontal row of said pegs or pins is in a plane substantially ninety degrees to the next adjacent horizontal row of pins. Said pins 90 are in non-aligned positions circumferentially of the pin shaft and in such positions that each row of pins constitute a different combination of positions longitudinally of the pin shaft 88 and so that each such row of radial pins 90, when positioned in horizontal direction inwardly of the device, will act as stops or obstructions to pivoting movement of the counterweight portion 79 of certain of the rocker members 78. It will be noted that the length of the counterweight portions 79 or rocker members 78 is such that they extend below a plane passing through the longitudinal center of pin shaft 88, and that when certain of the pins 90 are positioned toward said counterweight portions, the corresponding rocker members 78 will not pivot or rock to cause discharge of the balls which fall upon the cup portions of those rocker members.

As shown in elevation in Fig. 2 and in transverse cross section in Fig. 4, I provide an inclined trough 91, preferably made of metal, which has one end secured in the side bar 10b and its lower end secured in intermediate panel 14 and being in a position so that its balls which are discharged by pivoting movement of rocker members 78 will fall into said inclined trough 91 and roll to a suitable receptacle for reuse in successive plays.

Referring to the right hand portions of Figs. 1 and 5, I provide an optional pivoted pawl 92 which is pivoted at one end by a screw 93 for vertical movement to cause engagement of its forward bent end between any two adjacent sprocket teeth of the sprocket 84 so that the player may optionally releasably rock the indicia roller 82 and pin shaft 88 in the desired position during play of either one series or a part of one series of balls.

As shown in Fig. 2, the rockable pivotally mounted play table pivoted for side to side rocking movement as hereinbefore described, has its edge areas provided with a pair of downwardly depending metal hooks 94 which are connected by relatively yieldable springs 95 to lower horizontally extending anchoring hooks 96 as shown at the lower portion of Fig. 2. This spring-flexible anchorage of the side portions of the playing table provides for limited though adequate optional rocking movement of said playing table during the periods during which the balls are rolling downwardly thereof toward the rocker members 78.

I desire it to be understood that in the major portion of the foregoing I have directed the description to one of said play tables, only one complete one being shown in Fig. 2, and desire it

to be understood that where two or a plurality of such play tables were embodied in one game unit, that each of said play tables and associated parts would be preferably built similar to that hereinbefore described.

I will now describe one preferred method of play, this description being directed only to play upon one of said tables, it being understood that similar method of play would be followed as to any other additional play table unit where the particular structure embodies more than one play table. I desire it to be understood that my game device may be made and satisfactorily used with only one play table, as hereinbefore mentioned, with fully satisfactory results.

A player deposits a number of marbles or balls into the cup shaped receiving end 63 of a ball race 59, the balls rolling by gravity one after the other to line themselves in a row in the delivery end 59a of curved ball race 59 and with the foremost ball engaged against the inverted U-shaped brackets 72. Thereupon the player, desiring to deliver one ball at a time to the right hand playing table, will manually lower the left hand end of the pivoted ball race 61 to cause the right hand inclined trough or chute 69 to move upwardly to slightly raise and dislodge the foremost ball and to cause such ball to roll down said inclined chute 69 to a position in rockable race 61 adjacent the lower end of chute 69. Thereupon the player will pivot or rock the swingable ball race 61 to lower the right hand portion and raise the left hand portion to cause rolling discharge of the ball along said right hand end of said race 61 and into the receiving end 51 of the inclined race 50.

The player either before starting movement of the first ball or before discharging the ball from the swingable ball race into race 50 will select one of a series of horizontally aligned indicia, either numbers or other suitable indicia, borne on indicia shaft or roller 82, effecting such selection by presenting upwardly the selected row of said indicia and thereby causing horizontally extending pegs or pins 90 which are positioned correspondingly to said indicia, to obstruct pivoting and discharge movement of certain of the rocker members 78. So that the player may always have in view the indicia and their relative positions in corresponding rows as they are borne upon the roller 82, the corresponding four horizontal rows of numbers borne on said roller 82 may be affixed or reproduced by imprinting, labels or the like, upon the lower edge portions of each playing panel as partially illustrated at the right of Fig. 1. Having these rows of numbers in view in the same relative positions as they exist on the roller 82, the player may elect to play any one of said four rows of numbers and move and rotate the indicia shaft or roller 82 to present upwardly and to view said selected numbers.

The ball, being deposited in race 50, will roll therealong, the valve 55 being open to cause discharge of the ball through the spout 53 upon the upper portion of the playing table or playing panel 74.

As each ball is deposited, one at a time, upon the upper end of the inclined playing panel, such ball may roll entirely by chance to fall into any one of the cups 88 of rocker members 78. During such downward roll, the player may optionally rock the pivoted playing table by vertical movement of the fulcrumed lever 96 which is fulcrumed by suitable pivot (not shown) in the

frame side bar 13b as shown at the right of Fig. 1, the inner end of said lever contacted against the bottom surface of the playing panel.

As before stated, when a ball downwardly rolling on the playing panel drops upon the cup portion of rocker members 78, which is not obstructed from pivoting movement by one of the horizontally extending pins 90, the ball will thereupon be discharged in the described manner into trough 91 to be rolled out for reuse. When one or more of the balls drop upon those rocker members which are obstructed by pins 90 against pivoting movement, the balls will remain in said cups and in the position illustrated in Fig. 4, and upon completion of play of the desired number of balls, the player will add together the numbers which are represented by the rocker member cup-retained balls to determine the score for the particular series of play.

Two or more players may use the same playing table in the aforescribed manner and may optionally record their scores to determine which contains the highest total of scores in a given number of plays. A similar method of score computation may optionally be followed where separate playing tables are used by two players, and I desire it to be understood that other methods of scoring may be practiced with the use of my game device.

If a player desires that one or more balls of a particular series being played be prevented from reaching the playing table, he may cause discharge thereof from either one of the inclined races 47 or 50 by opening either one of the valves 54 or 55 to prevent the ball from entering the aforesaid discharge spout and to cause the ball to be thrown from the said inclined races by movement in the desired direction of one or the other of the pivoted levers 36 or 37. I desire it to be also understood that in place of direct manual swinging movement of the swingable ball race 61, the player may utilize therefor either one or the other of the fulcrumed levers 33 or 36 to effect rocking or swinging movement of said race 61 in the desired direction.

I am aware that various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof.

I claim as my invention:

1. In a game device, in combination, a frame-like support; a longitudinally inclined table on said support having a transversely rocking movement; an upwardly extending standard; inclined chutes mounted adjacent said standard and having a partially obstructed delivery end opening; a manually tiltable ball track pivoted on said standard; a pair of pawls pivoted on said track and adapted when moved upwardly to release a ball at the delivery opening of said chute to cause it to roll on said track; a runway connected to said frame-like support and adapted to cause a ball delivered thereon to be deposited on the upper end of said table; a plurality of transversely aligned indicia bearing fulcrumed levers having cup-like portions in positions so that the balls rolling upon said bed will fall thereupon to normally tilt said levers to discharge a ball below the playing surface, and a manually rotatable shaft having non-uniform rows of pins thereon and being positionable to cause the pins of one

said row to obstruct the tilting movement of said levers.

2. In a game device, in combination, a frame-like support; a longitudinally inclined table on said support having a transversely rocking movement; an upwardly extending standard; inclined chutes mounted adjacent said standard and having a partially obstructed delivery end opening; a manually tilttable ball track pivoted on said standard; a pair of pawls pivoted on said track and adapted when moved upwardly to release a ball at the delivery opening of said chute to cause it to roll on said track; a runway connected to said frame-like support and adapted to cause a ball delivered thereon to be deposited on the upper end of said table; a plurality of transversely aligned indicia bearing fulcrumed levers having cup-like portions in positions so that the balls rolling upon said bed will fall thereupon to normally tilt said levers to discharge a ball below the surface of said inclined table; a manually rotatable shaft having non-uniform rows of pins thereon and being positionable to cause the pins of one said row to obstruct the tilting movement of said levers, and a multi-surfaced indicia and number bearing roller journaled in said support and adjacent said shaft, and cooperating gears on said shaft and said roller to cause the same to rotate simultaneously to thereby present a visible and varying set of indicia as applicable to each row of obstructing pins of said shaft.

3. In a game device including a supporting frame and an inclined playing table, and having manually operable means for selectively delivering balls to the normally higher portion of said table, a plurality of adjacent lever elements, each fulcrumed intermediate its ends and on a portion of said support and having an upper concave portion adapted to receive a ball rolled from said table; each of said lever elements being adapted to rock when a ball falls thereon to discharge the ball; a rotatable shaft bearing spaced apart pins thereon in staggered relationship, a portion of said pins being adapted to engage certain of said levers when a ball falls on their upper portions to thereby prevent rocking and ball-discharging movement of certain of the levers, and indicia adjacent each of said levers adapted to designated varied values.

4. In a game device including a supporting frame and an inclined playing table, and having manually operable means for selectively delivering balls to the normally higher portion of said table; a plurality of adjacent aligned lever elements, each fulcrumed intermediate its ends and on a portion of said support and having an upper concave portion adapted to receive a ball rolled from said table; each of said lever elements being adapted to rock when a ball falls thereon to discharge the ball; a rotatable shaft bearing rows of spaced apart pins thereon in staggered relationship, a portion of said pins being adapted to engage certain of said levers when a ball falls on their upper portions to thereby prevent rocking and ball-discharging movement of the levers; an elongated roller journaled in said support and substantially adjacent the upper portions of said aligned levers, said roller bearing numbers thereon to designate said levers respectively, and inter-engaging gears on said roller and on said shaft to thereby change the designated numbers applicable to certain levers

according to the row of pins presented to obstructing positions.

5. In a game apparatus, a supporting frame; an inclined ball-carrying chute; a tilttable track fulcrummed intermediate its ends and on said frame; a ball release lever pivoted on said tilttable track and adapted to release a ball from the discharge end of said chute and onto said track; an inclined playing table mounted in said frame; 10 inclined tracks mounted on said frame adapted to convey a ball discharged from said tilttable track to the upper end of said table; a plurality of adjacent aligned lever elements, each fulcrummed intermediate its ends and on a portion of said support and having an upper concave portion adapted to rock when a ball falls thereon to discharge the ball; a rotatable shaft bearing rows of spaced apart pins thereon in staggered relationship, a portion of said pins being 15 adapted to engage certain of said levers when a ball falls on their upper portions to thereby prevent rocking and ball-discharging movement of the levers; an elongated roller journaled in said support and substantially adjacent the upper portions of said aligned levers, said roller bearing numbers thereon to designate said levers respectively; and inter-engaging gears on said roller and on said shaft to thereby change the designated numbers applicable to certain levers 20 according to the row of pins presented to obstructing positions.

6. In a game device including a ball receptacle, an inclined playing table; inclined track means and means for releasing a ball from said receptacle upon said track means, said track means being adapted to deliver the balls on a playing table; a plurality of tilttable rockable lever elements mounted in aligned adjacent positions at the lower end of said playing table, said 25 lever elements being adapted to discharge a ball on pivoting movement; a roller member journaled in said frame substantially adjacent said lever elements though spaced therefrom; a plurality of rows of spaced apart obstructing pins in 30 said roller, said pins being positioned to obstruct the tilting of certain of said lever elements to thereby cause certain of said lever elements to retain balls thereon, and indicia on said roller to thereby permit computation of those indicia designating the ball-retaining levers at the completion of each play or series of play.

7. In a game apparatus having an inclined playing table and manually operable mechanism for selectively delivering the balls to the upper end portion of said inclined playing table, said mechanism including a pivotally mounted ball race; a plurality of pivotally mounted rocker elements adjacent the lower end of said inclined playing table, each of said rocker elements having a ball-receiving cup-like portion and an extended finger-like portion normally depending downwardly; and selectively movable variable indicia-bearing means mounted for rotatable movement substantially adjacent said pivoted ball obstructing members, said indicia bearing means including a rotatable shaft, and a plurality of spaced apart pegs extending radially from said shaft, said pegs being adapted in varied positions to hold certain of the ball obstructing members against ball-discharging movement.

PETER KYSKA.
